(57) **CLAIM**

The ornamental design for a flow alarm device housing, as shown and described.

DESCRIPTION

FIG. 1 is a perspective view of a flow alarm device housing embodying our new design;

FIG. 2 is a front view thereof;

FIG. 3 is a side view thereof;

FIG. 4 is another side view thereof;

FIG. 5 is a top view thereof;

FIG. 6 is another top view thereof;

FIG. 7 is a bottom view thereof; and,

FIG. 8 is another perspective view thereof.

The dashed lines immediately adjacent to the shaded areas in the figures represent the boundaries of the claimed design. The dashed lines in the figures illustrate the portions of the design that form no part of the claimed design. None of the broken lines form any part of the claimed design.
